William Gorman

INVENTOR.

United States Patent Office.

WILLIAM GORMAN, OF NEW BRITAIN, CONNECTICUT, ASSIGNOR TO RUSSELL & ERWIN MANUFACTURING COMPANY, OF SAME PLACE.

Design No. 4,474, dated November 15, 1870.

DESIGN FOR A CAR-LOCK.

The Schedule referred to in these Letters Patent and making part of the same.

To all whom it may concern:

Be it known that I, WILLIAM GORMAN, of New Britain, in the county of Hartford and State of Connecticut, have invented and originated a new Design for Car-Locks; and I do hereby declare that the following specification, taken in connection with the drawing making a part of the same, is a full, clear, and exact description thereof.

Figure 1 is a front view of the lock and the keeper.

Figure 2 is an end view.

The lock A, illustrated in the drawing, is of that class known as "rim-locks," which are intended to be set upon the surface of the door-stile instead of being let into a mortise cut therein.

In the drawing—

a is a molding, which defines the edge of the lock-case, as well as of the keeper B, and separates the ornamental design upon the face of the lock, and of the keeper from that upon the sides.

This molding, in the case of both lock and keeper, intersects with a rounded edge plate, b, appropriate to each.

The design of the face of the lock A commences with a central rosette, c, inclosed in a four-sided figure, whose exterior lines curve inward, and whose inner lines are filled out, so as to be nearly concentric

with the outlines of the rosette, and also to show Gothic points at the angles where the curved lines of the figure meet.

From each of the angles of the figure radiates a trefoil, as shown, while alternate with them, and springing from the middle point of each of the curved sides of the figure, radiates a leaf and scroll figure, as represented.

The edge of the molding a is ornamented with cinque foils alternate with points.

The design upon the face portion of the keeper B is that of cinque foils, alternate with points.

The sides of both lock and keeper are ornamented with lotus leaves, arranged alternately with trefoils, separated from each other by Gothic arches resting on bands and scrolls.

All the ornamental work described and represented is in relief upon a frosted or a plain ground.

What I claim as my invention, and desire to secure by Letters Patent, is—

The ornamental design for a car-lock and keeper, herein described, and shown in the drawing.

WILLIAM GORMAN.
